UNITED STATES PATENT OFFICE.

CARL H. BISSELL, OF SYRACUSE, NEW YORK, ASSIGNOR TO CROUSE-HINDS COMPANY, OF SYRACUSE, NEW YORK, A CORPORATION OF NEW YORK.

AUTOMATIC SWITCH.

1,268,426.

Specification of Letters Patent.

Patented June 4, 1918.

Application filed December 3, 1913. Serial No. 804,538.

To all whom it may concern:

Be it known that I, CARL H. BISSELL, a citizen of the United States, and a resident of Syracuse, in the county of Onondaga and State of New York, have invented a new and useful Automatic Switch, of which the following is a specification.

This invention has for its object the production of an automatic switch which is particularly simple in construction and highly efficient and durable in use, and it consists in the novel combinations and constructions hereinafter set forth and claimed.

In describing this invention, reference is had to the accompanying drawings, in which like characters designate corresponding parts in all the views.

Figures 1 and 2 are plan views, partly broken away, of this switch illustrating, respectively, the positions of the parts when the switch is open and closed, Fig. 2 being partly broken away.

Fig. 2^a is a fragmentary sectional view looking to the left of the upper part of Fig. 2, the switch being shown as open.

Fig. 3 is a section on line A—A, Fig. 1.

Fig. 4 is a detail view of a part of the circuit changing switch.

Fig. 5 is a diagrammatic view illustrating the electric wiring.

This automatic switch comprises, generally, a movable switch member, means for actuating the member in opposite directions to open and close the switch including electro-magnetic means, magnetizable means operated by the electro-magnetic means, power transmitting means operated by the magnetizable means and connected to the switch member, the electro-magnetic means being connected in an operating circuit having a reversing switch therein by which the energizing of the electromagnetic means is controlled, whereby the electromagnetic means acts on the magnetizable means in one direction to open the switch and in the opposite direction to close the switch.

In the illustrated embodiment of my invention, the electromagnetic means comprises two magnets, or a double magnet. The magnetizable means is an armature arranged to be acted on by the magnets; and the power transmitting means includes a toggle connected to the switch member and to a part connected to the magnetizable means. The joint of the toggle preferably

moves into or beyond the dead center line of the toggle when the switch is closed, and a hammer in the form of a magnetizable member is employed to strike a blow to start the operation of the toggle; that is, to carry its joint out of the dead center line during the initial part of the opening movement of the switch member. The windings of the magnets are designed to be connected in different branches of the operating circuit which is controlled by a manually operated circuit changing switch, and a circuit breaker is operated by the magnetizable means, the circuit breaker having conductors arranged in the branches of the operating circuit and operating to open one branch while the other is closed and to break the circuit through the active magnet after said magnet has performed its work, and to close the branch through the other magnet so that when the circuit changing switch is again operated, the latter magnet will be energized. The magnets are here shown as solenoids and the magnetizable means or armature as a core.

1 is the switch member having conductors 2 movable into and out of engagement with terminals 3 on a bar or conductor 4 located in the main or feed circuit to be controlled by the switch member 1, the switch member having suitable contacts 2^a similar to the contacts 2, which contacts 2^a engage terminals 5 which are similar to the terminals 3 and which are connected to fuse terminals 6 leading to the load or lighting circuits through fuses 7. The conductor 4 is connected in the main line of the circuit through terminal 8.

The switch member 1 is, in this embodiment of my invention, movable rectilinearly, and is provided with guides or rods 9 near its opposite ends which slide in suitable openings formed in the supporting frame 10 of the switch. This frame 10 and the terminals 5, 6 and conductor 4 are mounted upon a suitable insulating base or board 11, the bar 4 being offset from the base by pillars as the pillar 4^a Fig. 2^a at each end.

12 and 13 are the solenoids, and 14 is a core within the solenoids and common to both of the same. 15 and 16 designate the links of a toggle which are pivoted together at their inner ends at 17, the outer or lower end of the link 16 being pivoted at 18 to the frame 10 and the outer or upper end of the

link 15 being pivoted at 19 to a collar 20 which is clamped on one of the rods 9. There are two of these toggles alike in construction, and located beyond opposite ends 5 of the solenoids 12 and 13, that is, in position to be connected by a rod 21 extending axially of the solenoids and upon which the core 14 is mounted. Said rod 21 is connected at its ends to the links 16 of the toggles by pin-and-slot connections, the slots 22 of which are formed in the links and the pins 23 of which are provided on the rod. In order to prevent turning of the rod, it is provided with arms 24 at its opposite ends having 10 bearings 25 which move along laterally extending guide rods 26 provided on the frame 10 and extending parallel to the rod 21. The pins 23 are provided directly upon the hubs of the arms 24.

20 Obviously, when the solenoid 12 is energized, the core 14 will be pulled to the right, Fig. 1, moving the rod 21 therewith, operating the switch member 1 and closing the switch; and when the solenoid 13 is operated, the core 14 will be pulled to the left returning the toggle from its position shown in Fig. 2 to that shown in Fig. 1, thus opening the switch.

The joint 17 of each toggle is designed to 30 be moved into or beyond the dead center line of the toggle, that is, a straight line passing through the pivotal points 18 and 19, in order that the switch will be held tightly in its closed position, and the movement of the toggle is limited by a suitable stop as the lower end wall 22^a of each slot 22 against which the pin 23 strikes when the toggle is in its extended position.

In order to start the operation of the toggle 40 when it is in its position shown in Fig. 2, means is provided for moving the pins 17 out of the dead center lines of the toggles, said means comprising an electromagnetically operated hammer in the form of a core 45 27 located within the solenoid 13 and slideable along the rod 21 against a head 28 fixed on the rod. Hence, when the solenoid 13 is energized, when the parts are in their position shown in figure 2, the core 27 is pulled 50 violently to the left and strikes against the head 28, thus operating the toggles to carry their joints out of the dead center lines.

The solenoids 12, 13, or the coils thereof, are designed to be connected in different 55 branches of the operating circuit, in which is located a manually operated reversing or pole changing switch 29 of any suitable construction; and in order that the solenoid made active by the operation of the switch 60 29 may be rendered inactive when it has performed its work, a circuit breaker is provided having conductors located in the legs 30 and 31 of the branches in which the solenoids are respectively connected, one of the conductors being in position to close the circuit

through one branch when the other conductor is in position to break the circuit through the other branch. Said circuit breaker is in the nature of a toggle comprising two levers 32, 33 pivoted between their ends at 70 34, and 35 to the frame 10, the inner arms of said levers being pivoted together by a pin-and-slot joint 36 and the outer arms being connected by a spring 37 which effects a quick break operation when the joint 36 75 passes through the dead center line of the circuit breaker, that is a line passing through the centers 34 and 35.

The arm 33 includes two conductors 38 and 39 which are insulated from each other 80 and movable between terminals 40 and 41 located respectively in the branches 30 and 31 leading to the solenoids 12 and 13.

The circuit breaker is operated by the rod 21, and it is connected thereto by a lost 85 motion connection; and as here shown, the rod 21 is provided with a shoulder 42 which moves between separated shoulders 43 and 44, so that the circuit breaker will not be operated until the rod 21 and toggle links 90 15 and 16 and switch member 1 have nearly reached the limit of their movement in either direction. When the parts are in the position shown in Fig. 1, the circuit breaker is in such position that its conductor 38 95 closes the branch circuit 30 through the solenoid 12, and hence upon the operating of the switch 29 to close the circuit through the branch 30, the solenoid will be energized, and the switch arm 1 and the circuit 100 breaker moved to their positions shown in Fig. 2, so that the conductor 39 of the circuit breaker closes the circuit of the branch 31 through the solenoid 13, and the conductor 38 is moved to break the circuit 105 through the branch 30 connected to the solenoid 12. However, the solenoid 13 is not energized as the manually operated switch 29 is in such position that it closes the circuit through the branch 30 which has just 110 been broken by the switch conductor 38.

During the energizing of the solenoid 12, the core 14 is pulled to the right causing the switch arm 1 to be closed. When it is desired to again reset the parts to their original position, the switch 29 is again operated and closes the branch 31 leading to the solenoid 13, and as this branch has been closed by the conductor 39 during the previous operation of the switch arm 1, the solenoid 12 is energized and the core 14 pulled to the left, and the toggles operated to open the switch 1. During this movement, the conductors 38 and 39 close the branch 30 and open or break the branch 31, respectively. 115 120 125

What I claim is:—

1. An automatic switch comprising a movable switch member, two solenoids arranged in axial alignment and designed to be alternately energized, a core common to both 130

solennoids and arranged to be acted on in opposite directions by the solennoids, means for transmitting the movement of the core to the switch member including a toggle, the joint of which is movable into the dead center line of the toggle, a rod connecting the core and the toggle, the rod having a head thereon, and a core located within one solennoid and arranged to be actuated thereby to strike the head and move the rod to shift the toggle to carry the joint thereof out of the dead center line of the toggle, substantially as and for the purpose set forth.

2. An automatic switch comprising a movable switch member, two solennoids arranged in axial alinement and designed to be alternately energized, a core common to both solennoids and arranged to be acted on in opposite directions by the solennoids, means for transmitting the movement of the core to the switch member including a toggle, the joint of which is movable into the dead center line of the toggle, a rod connecting the core and the toggle, the rod having a head thereon, the rod being connected to one of the links of the toggle by a pin-and-slot connection, and a core located within one solennoid and arranged to be actuated thereby to strike the head and move the rod to shift the toggle to carry the joint thereof out

of the dead center line of the toggle, substantially as and for the purpose described.

3. An automatic switch comprising a movable switch member, two solennoids arranged in axial alinement and designed to be alternately energized, a core common to both solennoids and movable thereby in opposite directions, means for transmitting the movement of the core to the member including a pair of toggles located beyond opposite ends of the core, the joints of the toggles being movable into the dead center lines of the toggles, and a rod upon which the core is mounted, connected to the toggles, a core located within one of the solennoids and slideable on the rod, and a head mounted on the rod and fixed thereto and arranged to receive the impact of the sliding core to move the joints of the toggles out of the dead center lines of the toggles, substantially as and for the purpose set forth.

In testimony whereof, I have hereunto signed my name in the presence of two attesting witnesses, at Syracuse, in the county of Onondaga, in the State of New York, this 26th day of November, 1913.

CARL H. BISSELL.
